PORTABLE TAPE RECORDER

Roland J. Kalb, Scarsdale, and Monte L. Levin, Roslyn Heights, N.Y., assignors to Steelman Phonograph and Radio Co., Inc., Mount Vernon, N.Y., a corporation of New York

Filed Aug. 7, 1959, Ser. No. 57,093

Term of patent 14 years

(Cl. D26—14)

FIG. 1

FIG. 2

Des. 188,984

PAGE 2

FIG. 3

FIG. 4

FIG. 5

Fig. 1 is a front perspective view of a portable tape recorder, showing our new design;

Fig. 2 is a front perspective view, to a reduced scale, with the cover in open position;

Fig. 3 is a side perspective view, to a reduced scale;

Fig. 4 is an opposite side perspective view, with the cover removed; and

Fig. 5 is a front perspective view, thereof.

The back, not shown, is substantially plain.

We claim:

The ornamental design for a portable tape recorder, substantially as shown and described.
